UNITED STATES PATENT OFFICE

JULES LUCIEN LENOUVEL AND PIERRE CHAPSAL, OF PARIS, FRANCE, ASSIGNEES TO
MAGNETYP S. A., OF COLOGNY, SWITZERLAND, A CORPORATION OF SWITZERLAND

METHOD OF PRINTING MUSIC

Original application filed July 15, 1927, Serial No. 206,041, and in France February 25, 1927. Divided
and this application filed June 10, 1929. Serial No. 369,691.

Our invention relates to a method of printing music in an apparatus of the type disclosed and claimed in our copending application Serial No. 206,041, filed July 15, 1927, 5 now Patent No. 1,726,110, August 27, 1929 of which the present application is a division.

According to the said copending application the music is composed upon a magnetic or electro-magnetic table carrying lines analogous to musical staves on an enlarged scale in connection with small type pieces of magnetic metal having the form of the usual characters, on the same enlarged scale as the staves. Upon the said type pieces is applied 10 a sheet of paper carrying the musical staves corresponding to the ones formed on the table, and thus the composed music can be printed upon the sheet. According to our present method of printing a negative of reduced size 15 is obtained by photography from said sheet, which is reproduced by any of the well known methods in the art.

Only such parts of the apparatus will be hereinafter disclosed as have a direct bearing 20 on our method, reference being had to our copending application for details which do not come within the scope of the present application.

In the apparatus of the type referred to 25 the printing paper travels from a feeding reel placed at one side of the magnetic table, through a pair of actuating rollers disposed at the other side of the said table. The paper is preferably applied upon the said table by 30 means of a vertically movable plate, and it is then drawn forward at the end of the operation and passes over an inking roller by means of which the staves are printed upon the paper.

The electro-magnetic table is arranged to 35 be horizontally slidable so that it may be brought from under the said printing plate and thus become disengaged during the coming position.

The lines upon the said table are formed by 40 cords which are stretched from one end to the other, and the type pieces have suitable notches formed on the underside by which 45 they may be disposed upon the said cords, so

that they may be readily placed in the proper position.

According to our present method, the printed sheet after leaving the machine is finished or corrected by employing an air brush 55 in connection with suitable stencils in order to form upon the said sheet all the musical characters or signs which may be necessary, such as slurs, braces, ties for quavers, or the like. Any errors in the notes or other parts 60 are preferably corrected by pasting upon the faulty portion, a piece of paper carrying the correct notes, and this correction is quite visible when the sheet is subsequently reduced by photographic means. 65

Further objects of our present invention will be obvious from the following description when taken in connection with the accompanying drawing forming a part of this specification and illustrating the general features of our apparatus in connection with 70 which our method is used.

In the drawing—

Fig. 1 is a general elevational view of the machine; 75

Fig. 2 is a cross section on the line A—A of Fig. 1; and

Fig. 3 is an end view of the machine, with the electro-magnetic table moved to the front of the printing plate. 80

Referring to the drawing more in detail, our apparatus comprises a horizontal table whose width is about twice the width of the electro-magnetic plate or type carriage A which is mounted upon the same by means of the rollers 2 adapted to travel upon the rails 3 under the action of a hand wheel 4 which drives by means of bevel gearing, a shaft 5 to which are keyed the pinions 6 coaxing with the racks 9. 85

The magnetic table A consists of a cast iron plate 7 of rectangular form surrounded by a flanged portion 7a of flat shape upon which is disposed the coil of conducting wire 8. The said coil carries a current which is preferably regulated by a rheostat (not shown) thus energizing the whole surface of the plate 7 forming the core of the electro-magnet. Above the plate 7 is disposed a steel plate 10 into which are inserted, according to a set of longitudinal lines corresponding to the lines 100

of the musical staff, the steel pole-pieces 12 which are flush with the upper surface of said plate and are separated therefrom by a bushing 13 of a non-magnetic metal or alloy such as aluminum, the said pole-pieces serving to transmit the magnetic flux from one plate to the other. The disposition of the said pole-pieces may be as desired, and their number should be as large as possible in order to obtain the best distribution of the magnetic flux upon the said table.

Across the said table are stretched from one end to the other various sets of cords 14 in parallel position which are optionally metallic, the ends of the cords being wound upon the stretching pegs 15. Each set of cords comprises a series of five cords 14 corresponding to five lines of the staff. Between the lines of the staves are disposed other cords 14^a adapted to receive and fix in proper position the type pieces corresponding to the notes between the lines, said cords being of a different color so as to avoid any confusion with the lines of the staff.

25 At the sides of the table A are disposed the flat bars 10^a having the same height or thickness as the type pieces set up on said table, said bars serving to limit the descent of the platen, thus preventing any damage to the type pieces.

Above the main table or base 1 is disposed, over one-half the width thereof, a frame comprising two vertical uprights 18 and a horizontal cross-piece 19, which supports the type box 20 which also rests upon a cross-piece 21 connecting the said uprights. The said type box contains the different pieces of type for composing the music. A screw 22 provided with weighted arms is engaged in a nut 23 mounted on the cross-piece 19 and it controls the upward and downward motion of a platen 24 which is vertically slidable between the uprights 18. The said platen has the same width as the table A, and its lower side is faced with a felt member 25 which is secured at one end *a* to one side of the platen while its other end is wound upon a square shaft 26, held by pawls 16, whereby the said felt member may be more or less stretched.

50 On one side of the said frame is disposed, upon a suitable support, a roll of paper 27 which has the same width as the table A. The paper band 28 travels over the whole length of the table and is engaged between two drums 29—30 mounted at the other end of the frame. The drum 30 may be rotated as desired by a suitable mechanism, and the paper band is finally wound upon a reel 31. Two pairs of rollers 28^a at each end are employed to hold the paper and to stretch it below the plate, and the said rollers are pressed together by means of an eccentric.

Upon the cylinder 29 are formed sets of five annular projecting parts of flanges 33 with sharp edges which make contact with

the paper wound on the drum 30. Said flanges are also in contact with the inking rollers 32—34 which operate in an ink vessel 35, and the said rollers thus print upon the paper various parallel lines corresponding to the musical staves.

The operation of our apparatus is as follows:

To set up the music, the hand-wheel 4 is used to bring the type-carriage A as near as possible to the front edge of the table 1, and the magnetic flux is so regulated as to produce only a slight adhesion of the type pieces, so that they may be readily put in place. The music may be set up even without energizing the electro-magnet, and the type characters will remain in place upon the table. The work is set up as above mentioned by placing the type characters upon the cords 14 which form the lines of the staff. When the piece of work has been completed the strength of the current, and hence the adhesion of the type, is increased. The type is inked, and the type carriage A is brought below the platen 24. The paper band 28 being engaged between the rollers 28^a is stretched thereby and the platen 24 is lowered by means of the screw 22. Due to the use of the felt pad 25 and the slight amount of slack resulting from the free unwinding of the reel 27, the notes will be printed instantaneously in a perfect manner. The platen 24 is then raised, and the rollers 29 and 30 are rotated so as to draw forward the paper a distance equal to the printing thereon, and the flanges 33 then print the lines of the staff as the paper travels forward.

The printed band of paper is then cut off and the electric circuit is broken in order to remove the type characters which are employed for other pieces of work.

One advantage which is obtained with our said apparatus resides in the fact that the work may be corrected in a very simple manner, for in methods known in the art of printing music it is a long and complicated matter to make such corrections.

According to our method, on the large size printed sheet obtained from the machine hereinbefore described we make all the desired corrections by pasting upon any faulty notes or like characters, suitable pieces of paper containing the corrected characters, and since we subsequently photograph the said sheet on a reduced scale, such corrections will appear quite satisfactory and invisible.

When the sheet is removed from the printing machine, certain signs or parts may be lacking, such as slurs, braces, ties for quavers, or the like, which are difficult to form in type by reason of their variable size so that these will be wanting in the printed sheet. These corrections may be readily made on the sheet, according to our method, after the sheet has left the press, by means of an air brush and suitable stencils.

Our method of printing likewise contemplates setting up pieces of music together with the words, or by printing or otherwise forming the words by a separate process and then pasting the same upon the sheet of music before it is photographed.

Having described our invention what we claim as new and desire to secure by Letters Patent is:

1. The method of printing music which comprises, printing the musical characters on a plain sheet of paper to an enlarged scale, superposing the staff lines on said characters to a corresponding scale subsequent to said printing operation, supplying the signs which are difficult to print due to their varying sizes by means of an air brush and stencils to the said corresponding scale, and subsequently photographically reducing the sheet of music thus obtained to the size required.

2. The method of printing music which comprises, printing the musical characters on a plain sheet of paper to an enlarged scale, superposing the staff lines on said characters to a corresponding scale subsequent to said printing operation, correcting errors by pasting strips of paper on said printed paper containing the desired corrected characters and subsequently photographically reducing the sheet of music thus obtained to the size required.

3. The method of printing music which comprises, printing the musical characters on a plain sheet of paper to an enlarged scale, superposing the staff lines on said characters to a corresponding scale subsequent to said printing operation, supplying the signs which are difficult to print due to their varying sizes by means of an air brush and stencils to the said corresponding scale, correcting errors by pasting strips of paper on said printed paper containing the desired corrected characters, and subsequently photographically reducing the sheet of music thus obtained to the size required.

4. The method of printing music which comprises, printing the musical characters on a plain sheet of paper to an enlarged scale, superposing the staff lines on said characters to a corresponding scale subsequent to said printing operation, correcting errors by pasting strips of paper on said printed paper containing the desired corrected characters, pasting the words of said music on said printed paper by pasting the paper containing them thereon and subsequently photographically reducing the sheet of music thus obtained to the size required.

5. The method of printing music which comprises, printing the musical characters on a plain sheet of paper to an enlarged scale, superposing the staff lines on said characters to a corresponding scale subsequent to said printing operation, supplying the signs

which are difficult to print due to their varying sizes by means of an air brush and stencils to said corresponding scale, pasting the words of said music on said printed paper by pasting the paper containing them thereon and subsequently photographically reducing the sheet of music thus obtained to the size required.

6. The method of printing music which comprises, printing the musical characters on a plain sheet of paper to an enlarged scale, superposing the staff lines on said characters to a corresponding scale subsequent to said printing operation, correcting errors by pasting strips of paper on said printed paper containing the desired corrected characters, supplying the signs which are difficult to print due to their varying sizes by means of an air brush and stencils to said corresponding scale, pasting the words of said music on said printed paper by pasting the paper containing them thereon and subsequently photographically reducing the sheet of music thus obtained to the size required.

In testimony whereof we have signed this specification.
